UNITED STATES PATENT OFFICE.

JULIUS C. TORCHIA, OF HAZLETON, PENNSYLVANIA.

LAST SUPPORT.

Application filed November 7, 1923. Serial No. 673,303.

To all whom it may concern:

Be it known that I, JULIUS C. TORCHIA, being a citizen of the United States, residing at Hazleton, in the county of Luzerne and State of Pennsylvania, have invented certain new and useful Improvements in Last Supports, of which the following is a specification.

This invention relates to improvements in shoemakers' last supports and has as its general object to provide a support so constructed that the last supported thereby may be adjusted to assume any desired position found most convenient in the various operations of manufacturing a shoe or repairing the same.

One of the objects of the present invention is to provide a last support which may be adjusted so as to support the last at practically any desired elevation thereby adapting the device for use by a workman who is seated as well as for use by a workman who prefers to stand while working.

Another object of the invention is to provide a last support so constructed as to permit of adjustment of the last rotatably to assume any desired position and likewise provide for angular adjustment of the last supporting means as well as the rotative adjustment so that the last may be positioned for most convenient use in the operation of sewing.

Another object of the invention is to so construct the support and particularly the member thereof which directly supports the last, as to permit of angular adjustment of this member and at the same time provide for rotative adjustment of the last for the purposes above stated, means being provided for firmly holding the various parts of the support in their different positions of adjustment.

Another object of the invention is to provide a last support which will effectively withstand the impacts to which it is subjected and in which the noise produced by the impacts will be materially lessened.

In the accompanying drawings:

Figure 1 is a front elevation of a shoemaker's last constructed in accordance with the present invention; the supporting stand being shown in lowered position in full lines and in an elevated position in dotted lines;

Figure 2 is a side elevation of the support,

the member which directly supports the last being shown in upright position in full lines and in a tilted or angularly adjusted position in dotted lines;

Figure 3 is a vertical transverse sectional view through the last;

Figure 4 is a horizontal sectional view on the line 4-4 of Figure 2 looking in the direction indicated by the arrows;

Figure 5 is a horizontal sectional view taken substantially on the line 5-5 of Figure 2;

Figure 6 is a perspective view of one member of the last support;

Figure 7 is a similar view illustrating the member to which the holding strap for the last is connected.

The support embodying the invention comprises a stand including a relatively fixed member indicated in general by the numeral 1 and of hollow approximately cylindrical form, and an adjustable member which is indicated in general by the numeral 2 and is received within the member 1. The member 1 is provided at its lower end with a base which is indicated by the numeral 3 and which may be secured in any suitable manner to the floor surface upon which the last support is disposed. The member 1 is formed in its opposite sides with slots 4 and 5, and that side of the member 1 in which the slot 4 is formed

is disposed at an angle as best shown in Figures 1 and 3 of the drawings, so that this side of the last is provided with a relatively flat bearing surface 6 extending substantially throughout the height of the member 1 and inclined inwardly toward the axis of the member in an upward direction. The purpose of thus forming the member 1 will presently be set forth. At

its opposite side and at opposite sides of the slot 5, the member 1 is formed with parallel series of lugs or shoulders 7, the two series of lugs or shoulders extending substantially throughout the height of the said member 1. The member 2 is, like the member 1, of hollow substantially cylindrical form and is rotatably and vertically adjustably seated in the bore of the member 1 as best shown in Figure 3 of the drawings.

In order that the member 2 may be supported at various elevations, it is disposed to rest, at its lower end, upon a substantially circular head 8 which is vertically ad-

justable within the bore of the member 1. This head 8 is provided at one side with an arcuate boss 9 which projects into the slot 5 and is slidable therein, a similar boss 10 being provided at the opposite side of the member 8 and in like manner engaging in the slot 4. A diametric groove 11 is formed in the under side of the head 8, and the head is formed axially with an opening indicated by the numeral 12. A bolt 13 is fitted at its headed end through a washer 14 which is disposed against the bearing surface 6 of the member 1, the bolt 13 extending through the slots 4 and 5 and engaging in the groove 11 as shown in Figure 3. A binding nut 15 is fitted onto the threaded end 16 of the bolt 13 and may be tightened to bear against a block 17 which is loosely fitted upon the bolt and which block is designed to seat interchangeably between the lugs 7 upon the member 1, as shown in Figures 1 and 3 of the drawings. At this point it will be evident that when the parts are assembled and the nut 15 is tightened, the head 8 will be afforded firm support and will in turn constitute a firm support for the member 2. Due to the inclination given the surface 6 of the member 1 and the engagement of the washer 14 against this surface, impacts delivered to the member 2 during the lasting operation will only serve to more firmly wedge the washer 14 against the inclined side of the member 1 and enhance the binding action of the nut 15. In order that the member 2 may be most conveniently vertically adjusted within the member 1, a spring 18 is arranged about the bolt 13 and seats within the concavity of the arcuate boss 9 and bears outwardly against the block 17. Due to the provision of this spring, when the nut 15 is loosened, the block 17 will be shifted outwardly along the bolt 13 until it has cleared the lugs 7 whereupon the member 2 and the bolt 13 and the head supported thereby may be vertically adjusted to assume any desired position, the parts being again tightened or locked after the desired adjustment has been obtained.

At its upper end the member 2 is formed with a fixed head 19 which is interiorly cupped as indicated by the numeral 20 so as to snugly receive beveled annular boss 21 provided on the under side of a socket member which is indicated by the numeral 22. The peripheral portion of the socket member 22 overlies the upper edge or rim of the cupped head 19, and a cushioning ring 23 of rubber or any other suitable material is interposed between the overhanging peripheral portion of the socket member 22 and the said rim of the head 19. This cushioning ring serves to cushion the force of impact delivered to the last during the lasting operation and consequently serves to eliminate, to a great extent, the metallic noises which would otherwise attend the lasting operation. Rotatably seated within the opening of the socket member 22 is a cylindrical boss 24 formed at the lower end of a last supporting shank which is indicated by the numeral 25. The socket member 22 is provided at one side with an extension 26 which is bifurcated as at 27 to receive a pivot lug 28 formed upon an extension 29 of the head 19, a pivot pin 30 being fitted through the extension 26 and the lug 28 and serving to pivotally connect the socket member 22 with the head 19 so that the socket member may assume a position within the cupped head 19 or may be swung to a more or less tilted position as shown in dotted lines in Figure 2 of the drawings. By reference to Figure 2 it will be observed that the extension 26 is formed with a nose 31 and above the nose with a flat face 32. The extension 29 is provided with a downwardly projecting part 33 through which is fitted a bolt 34 having a spring 35 thereon bearing at one end against the head at the rear end of the bolt and at its other end bearing against the rear side of the part 33, and a binding nut 36 is adjustably fitted onto the projecting forward end of the bolt and is designed to be tightened to bind more or less firmly against a plate 37 which is provided with an opening 38 of a diameter greater than that of the bolt and which opening accommodates said bolt, the increased size of the opening permitting the plate 37 to fulcrum upon the bolt as illustrated in full and dotted lines in the said Figure 2. A stud 39 upon the forward end of the extension 29 projects through an opening in the plate 37 and serves to prevent any rotative movement of the plate about the bolt. The upper portion of the plate 37 projects in the path of movement of the nose 31 in the swinging movement of the socket member 22 about the pivot pin 30 and it will be evident by reference to Figure 2 of the drawings that when the socket member is swung downwardly to substantially horizontal position, the nose 31 will ride against the face of the plate 37 and due to the tension under which this plate is placed by the spring 35, the said member will be securely held in this position of adjustment. On the other hand, when it is desired to support the last in a tilted position as illustrated, for example, in dotted lines in Figure 2 of the drawings, the socket member 22 together with the last supporting shank 25 mounted therein may be swung to such position whereupon the flat face 32 of the extension 26 will seat against the face of the plate 37, and the parts will be locked in the new position of adjustment.

The last supporting shank 25 is provided

in its upper end with a socket 40 to receive the tang 41 of the last which is indicated by the numeral 42. In order that the last may be held in place upon the shank 25 5 and likewise in order that the shoe being manufactured or repaired may be held upon the last, a strap 43 is engaged over the instep portion of the last 42 and has its side stretches extending downwardly beside the 10 opposite sides of the shank 25 and through grooves 43' formed in the cylindrical lower end 24 of the said shank at diametrically opposite sides thereof. The lower portion of the strap passing through a loop 44 15 which is provided with a swivel 45 to which is connected the upper end of a spring 46, the lower end of the spring 46 being connected, as at 47, to the bolt 13 through the opening 12 in the head 8. The strap 43 is 20 provided with a buckle 48 to permit of adjustment of the strap as occasion may require.

In order that the cylindrical lower end 24 of the last supporting shank may be held 25 at various positions of adjustment in the socket member 22, a set screw 49 is threaded through an opening 50 formed in the said socket member 22 and may be tightened to bear against the said cylindrical lower end 30 24 of the said shank 25.

If desired, a brace 51 may be connected at its upper end to the upper portion of the member 1 of the support and secured at its lower end to the floor.

35 In order that the member 2 may be held in various positions of rotative adjustment with relation to the member 1, the said member 1 at its upper portion is split and formed at opposite sides of the split with ears 52 40 through which may be engaged a bolt 53 having a clamp nut 54 thereon, the nut being adapted to be tightened so as to contract the upper portion of the tubular member 1 about the member 2 for the purpose stated.

45 From the foregoing description of the invention and from the drawings it will be evident that the member 2 may be raised and lowered with respect to the member 1 so as to position the last at any desired elevation and that likewise the member 2 may be rotated within the member 1 so as to angularly adjust the last both while it is in the full line position shown in Figure 2 and while it is in the dotted line position shown 55 in said figure. It will also be evident that, independently of this adjustment, the last supporting shank 25 may be rotatably adjusted within the socket member 22 so as to position the last in a manner most convenient for use. It will also be evident that the last supporting shank 25 may be tiltably adjusted so as to position the last horizontally as shown in full lines in Figure 2 or in a more or less tilted or inclined position 60 as shown in dotted lines in said figure, and

that this adjustment does not in any way interfere with rotative adjustment of the said shank 25 in the socket member 22.

The support as hereinbefore described is 70 of course designed primarily for employment in shops but if it is desired to place upon the market a support which will be less expensive to manufacture and will be more suitable for home use, this may be accomplished by simply dispensing with the member 2, the supporting head 8 and its associated parts, the socket 22 and the parts associated therewith, and then mounting the cylindrical lower portion 24 of the last supporting shank 25 directly in the upper end 75 of the member 1, the lower end of the spring 46 being in this instance connected to a hook 55 located at any convenient point within the lower end of the said member 1.

Having thus described the invention, what 80 is claimed as new is:

1. In a last support, an upright comprising a hollow relatively fixed section, a section slidably adjustably fitted therein, means upon the adjustable section for the support 90 of a last, and means adjustable within the first mentioned section and constituting a rest for the said adjustable section; said means including a head slidable within the hollow portion of said fixed section, bosses 95 on said head fitting in corresponding longitudinal slots in said fixed section, and locking elements engaging said head and said fixed section.

2. In a last support, an upright comprising a hollow relatively fixed section, a section slidably adjustably fitted therein, means upon the adjustable section for the support 100 of a last, and means adjustable within the first mentioned section and constituting a rest for the said adjustable section; said means including a head slidable within the hollow portion of said fixed section, bosses on said head fitting in corresponding longitudinal slots in said fixed section, a bolt 105 engaging in a groove furnished in said head and extending through said slots, spaced lugs on said fixed section, and securing elements for the bolt adapted to engage between said lugs.

110 3. In a last support, an upright comprising a hollow relatively fixed section, a section slidably adjustably fitted therein, means upon the adjustable section for the support 115 of a last, the first mentioned section having a longitudinal slot and being provided at opposite sides of the slot with abutment portions, a bolt adjustable vertically with relation to the said first mentioned section and extending through the slot therein, a head 120 supported by the bolt and constituting a rest for the lower end of the adjustable section, a locking member upon the bolt for coaction with the abutment portions in the various 125 positions of adjustment of the head and bolt 130.

with relation to the said first mentioned member, and means adjustable to maintain the locking member in coactive engagement with the said abutment portions.

5. 4. In a last support, an upright comprising a hollow relatively fixed section, a section slidably adjustably fitted therein, means upon the adjustable section for the support of a last, a head adjustably arranged within the first mentioned section, the said first mentioned section having a slot and the head having a seating portion located opposite the slot, a bolt supporting the said head and having a threaded portion 10 extending through the slot and beyond the said first mentioned member, the first mentioned member at one side of the slot having a series of abutment portions, a locking member upon the bolt engageable interchangeably with the abutment portions in the vertical adjustment of the head within the said first mentioned section, the second mentioned section resting upon the head, a spring upon the bolt engaging the seating portion of the head and engaging against the locking member and tending to move the locking member out of engagement with the said abutment portions, and a nut threaded upon the bolt and coacting with the locking member, the nut being adjustable to urge the locking member into engagement with the abutment portions against the tension of 25 said spring.
5. In a last support, an upright comprising a hollow relatively fixed section, a section slidably adjustably fitted therein, means upon the adjustable section for the support of a last, the said first mentioned section having slots located in diametrically opposite sides thereof and extending longitudinally of the section, the section having a flattened exterior bearing surface extending longitudinally beside one of said slots, a se- 30

ries of abutment portions upon the said relatively fixed section extending beside the other slot, a head adjustable within the said fixed section, a bolt fitted through the slot in the said section, a washer upon the bolt bearing against the said flat surface of the said section, the bolt supporting the head, a locking member upon the bolt engageable interchangeably with the said abutment portions in the vertical adjustment of the head, the said head supporting the said adjustable section, and a nut threaded upon the bolt and coacting with the said locking member to hold the same in such engagement with the said abutment portions.

6. In a last support, an upright comprising a hollow relatively fixed section, the said section having a flattened bearing surface at one side of its exterior occupying a plane inclined upwardly and inwardly toward the axis of the section, the said section being formed in its said side with a longitudinally extending slot and with a similar slot in its diametrically opposite side, a series of abutment portions upon the exterior of the section extending beside the last mentioned slot, a section slidably adjustably fitted in the first mentioned section, a bolt fitted through the slot in the first mentioned section and having means contacting the flat bearing surface of the said first mentioned section, a head supported upon the bolt, the said head supporting the said adjustable section, a locking member upon the bolt coacting with the said abutment portions and engageable therewith interchangeably in the adjustment of the head and bolt, and a nut threaded upon the bolt and coacting with the locking member to hold the same in coactive engagement with the abutment portions.

In testimony whereof I affix my signature.
JULIUS C. TORCHIA. [L. s.]
